(57) CLAIM

I claim the ornamental design for pants, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of pants, showing my new design, according to the first embodiment;

FIG. 2 is a right side view thereof;

FIG. 3 is a rear view thereof;

FIG. 4 is a left side view thereof.

FIG. 5 is a front view of the pants, according to a second embodiment;

FIG. 6 is a right side view thereof;

FIG. 7 is a rear view thereof; and,

FIG. 8 is a left side view thereof.

The pants are shown with various trademarks, graphics, and/or indicia thereon, namely graphics exhibiting "PRO" and "NIKE" which form no part of the claimed design.
